QUILTING MACHINE

Filed Oct. 3, 1927

INVENTOR.
BY John R. Russell,
Walter N. Haskell,
his ATTORNEY.

UNITED STATES PATENT OFFICE

JOHN R. RUSSELL, OF STERLING, ILLINOIS

QUILTING MACHINE

Application filed October 3, 1927. Serial No. 223,807.

My invention has reference to quilting machines, and aims to increase the efficiency and usefulness of such devices. Material which is handled by machines of this class is of various sizes, three standard lengths being in common use, which lengths are approximately eight, eight and one-half, and nine feet. In order to handle all of these lengths it is necessary to make use of two or more frames in the machine, or else use a frame of a size which will handle the longest material, and make the shorter lengths thereon. This last method is not satisfactory, and the changing of frames requires a considerable amount of time and effort. The chief purpose of the present invention is to provide a frame which is subject to variations in length, by means of adjustments which can be quickly and easily made. The size of the frame can be thereby made to conform to the length of the quilt that is being worked, with a resultant ease of operation thereon.

The particular construction, arrangement, and operation of the machine will more fully appear from the following specification, reference being had to the accompanying drawings, in which;

Fig. 1 shows the invention in side elevation.
Fig. 2 is a plan view of the quilting frame, detached.

Fig. 3 is a detail, in section, of a modified form of the device.

Fig. 4 is a similar view, with the section detached.

Fig. 5 is an end view of the quilting frame, looking at the end piece 9.

The device is suspended by means of a pair of overhead supports 1, united by a cable 2, upon which is operable a carriage consisting of rollers 3 and bar 4 supported thereby. On the lower face of the bar 4 is pivoted a hanger 4^a, connected with the ends of a bar 5 by means of a pair of straps 6, provided with adjustment loops shown at 7, by means of which one or other of the ends of the bar 5 may be supported at a greater or lesser height, as desired. Suspended from the bar 5 is a quilting frame including a pair of end pieces 8 and 9, connected with the

bar 5 by hangers 10 and 11. The hanger 11 has a vertical end portion 12, slidable in a slot 13 in the bar 5, the upper end of said end portion being threaded and provided with a nut 14, by means of which the hanger can be held in adjusted positions. The upper bar of the hanger is also provided with a lug 15 slidable in the slot 13 and a groove 16 in continuation thereof, which lug holds the hanger in proper alignment with the bar 5.

Rollers 18, 19, and 20 have a pivotal mounting at one end in the end-piece 8, and at their other ends are provided with pins 21, (Fig. 5) which pins are rotatable in slots 22 in the end-piece 9. Catches 23 are pivoted on the face of the end-piece, and engage with the pins 21, to prevent accidental release thereof. The ends of the slots are curved inwardly, and when the material is in position on the rollers the tendency thereof is to prevent the outward movement of such rollers, which also assists in holding the pins 21 in the slots.

At that end of the rollers nearest the end-piece 9 each of said rollers is provided with a section 25, separated from the body of the roller by a reduced portion 26, also insertable in the slots in the end-piece 9, and additional sections 27 are also provided for the rollers, separated from the sections 25 by reduced portions 28. The reduced portions 26 and 28 may consist of rod extensions of the pins 21, or they may be formed by cutting away a sufficient amount of the rollers to leave a desired bearing. As shown in Figs. 1 and 2 the frame is arranged for operation with material of the greatest length, which will practically fill the space between the end pieces 8 and 9, and in case it is desired to work with material of less length the ends of the rollers are disconnected from the end-piece 9, and re-engaged therewith at the reduced portions 26 or 28, as may be required by the length of the material. To permit of this change the nut 14 is loosened and the position of the hanger 11 changed to conform to the adjustment of the end-piece. The nut 14 is then tightened again.

In operation, the upper layer of the quilt is rolled upon the roller 19 and the lining on the roller 18, and both layers attached to

the roller 20, for winding thereon as the work progresses. Any filling material is fed into the quilt between the rollers 18 and 19 in the usual manner.

5 In Fig. 3 the roller 18 is shown fitted with an extension 30, held in place by a bolt 31 held in the end of the roller 18. The outer end of the bolt is provided with a spool 32, for engagement with the slot 22 in the end-piece 9. As indicated, the section 30 would be designed to add enough to the length of the roller to provide for the operation of the frame with a quilt of next to the shortest length, and for the greatest length of material the section 30 is replaced by one of 10 double the length thereof. It will be understood that each of the rollers would be similarly provided with said extensions, permitting a variation in the working length of the 15 frame similar to that shown in Figures 1 and 2. In Fig. 4 the end of the roller 18 is shown without any sections attached thereto, and fitted with a short bolt 33 and spool 34 for connection with the end-piece 9.

20 25 The frame is operated in the usual manner with a sewing machine, the quilting being carried on between the rollers 19 and 20, and the work rolled up as the work progresses, as before mentioned.

30 What I claim, and desire to secure by Letters Patent, is:

A machine of the class described, comprising a support and carriage movable longitudinally thereof, a bar suspended from 35 said carriage and provided at its ends with hangers, a frame supported at its ends by said hangers, and quilting rollers in said frame provided at one of their ends with one or more sections forming spaced bearings for the support thereof, the hanger adjacent to the section ends of said rollers being 40 adjustable longitudinally of said bar to conform to the adjustments afforded by said sections.

45 In testimony whereof I affix my signature.
JOHN R. RUSSELL.
